UNITED STATES PATENT OFFICE.

LOFTUS B. CUDDY, OF BAYHEAD, NEW JERSEY.

APPARATUS FOR CRACKING OILS.

Application filed November 10, 1919. Serial No. 336,788.

The present invention relates broadly to oil-cracking stills, and more particularly to stills operating on the two-phase or continuous process.

- 5 The particular object of the present invention is to provide a still of this type with heating means so positioned and operated that the deposit of carbon necessitating intermittent operation of the still is obviated.
- 10 Another object of the present invention is to subject the still to the action of distributed or indirect heat or heated products of combustion, rather than to the direct blast of the heating medium.

15 Still another object of the present invention is to regulate the supply of heating medium so that a predetermined uniformity exists between the supply of the heating medium and the exhaust thereof through the 20 stack.

25 A further object of the invention is to so position the heating burners that the heated products of combustion are given a swirling or circular motion producing uniform heating of the still.

30 A still further object of the invention is to provide a still heated in the manner described and having the zone of highest temperature adjacent the upper or vapor portion of the still.

35 The foregoing and other objects, together with their attendant advantages, will be apparent as the invention becomes better understood by reference to the accompanying specification and drawings forming a part thereof, it being premised that changes may be made in the various details and the manner of operation within the scope of the appended claims, without departing from 40 the spirit of the invention.

In the drawings:

Figure 1 is a diagrammatic side elevation showing a still constructed in accordance with my invention;

45 Figure 2 is a cross section of the furnace on a larger scale;

Figure 3 is a vertical section of the still proper on an enlarged scale;

Figure 4 is a cross section of the still on the line IV—IV of Figure 3; and

50 Figure 5 is a detail sectional view of a portion of the still.

In carrying out the present invention, the oil to be cracked is pumped into the still 55 as the cracking proceeds, so that the operation is a continuous one. During the two-

phase cracking process the carbon which is rapidly freed from the oil and tends to collect on the sides of the still is continuously scraped off by specially constructed yielding 60 scrapers which are pulled around the inner curved surface of the still. The carbon thus scraped off is permitted to settle down through the oil and collect in a carbon receiver at the bottom of the still from which 65 it may be intermittently removed, as found desirable. Due to the action of the scrapers, the walls of the still are kept comparatively free of carbon, so that the operation of cracking the oil may be carried on continuously. 70

For the purpose of enabling the operator to maintain the oil at substantially the same level in the still, a gauge such as commonly used on boilers is connected through the 75 walls of the furnace into the still, thereby facilitating the determination of the oil level at a glance.

Referring more particularly to the drawings, I have illustrated a vertical still 2, 80 preferably comprising a cylindrical main body portion 4 and a convex head 5, secured thereto, as clearly illustrated in Figure 5. At the opposite end, the still preferably terminates in a conical portion 6, directing the 85 freed carbon through the outlet 7 into the carbon receiver 8. This receiver is, in turn, provided with gate valves 9 and 10 of any usual construction, permitting the intermittent removal of carbon from the receiver, 90 while the operation of cracking oil is continued.

Partially surrounding the still and spaced therefrom is a furnace 11 having a plurality of peep openings 12, adjacent the upper portion thereof, and through which conditions within the furnace may be observed. Within the furnace, and substantially intermediate the inner wall of the same and the wall of the still is formed a baffle wall 14, having 100 its upper portion 15 flared outwardly toward the furnace wall. In the preferred embodiment of my invention, the flared portion of the baffle wall is joined to the furnace wall, slightly below the plane of the peep openings 12, and is provided with a plurality of comparatively small or restricted openings 16, for the purpose hereinafter more fully set forth.

The furnace 11, which is preferably substantially polygonal in cross section, has extending through the walls thereof a plu-

rality of burners 17. These burners preferably are so positioned that they extend approximately tangentially with relation to the baffle wall 14, for producing a swirling 5 action therearound of the heated products of combustion within the heating chamber 18, the lower end of which is closed by a partition 19. The products of combustion, due to their circular or swirling action, become 10 uniformly mixed and rising gradually pass through the restricted openings 16 in the flared portion of the baffle wall and are directed against the upper portion of the still 2, preferably above the level of the oil there- 15 in. After expending their heat, the products of combustion escape through the outlets 20 into the circular flue 21, having communication with a suitable stack or stacks 22. These outlets 20 are preferably four 20 in number equidistantly spaced around the still. They also have a combined area substantially equal to the area of the stack, so that the waste gases are uniformly drawn away. In accordance with the present in- 25 vention, the combined area of the openings 16 in the baffle wall approximately equals the area of the stack, so that the feed of heated products of combustion to the still is restricted or regulated in proportion to 30 the exhaust of the same from the still. Due to this proportioning of the openings, I am able to produce a uniform heating to a high temperature of the upper or vapor portion of the still, without producing lo- 35 cally heated and cool portions, which result from subjecting the still to the direct blast of the products of combustion.

The oil to be cracked is fed through a 40 pipe 24 into a pump 25, which is preferably hand-controlled, so that it may be readily operated whenever desired to pump fresh oil into the still to maintain the proper level therein. From the pump, the oil passes through the pipe 26 into a heat interchang- 45 er 27, and feed-regulating valve 29, into the lower portion of the still. A gauge glass 30, having suitable connections 31 with the upper and lower portions of the still permits the operator to determine when the proper 50 level of oil within the still is reached.

The proper amount of oil having been 55 pumped into the still, the burners are placed in operation to produce an operating temperature of from 600 to 1500° F., in the furnace and from 600 to 1000° F., in the still, depending upon the oil to be treated. A pyrometer 32, extending into the furnace permits the operator to determine the heat 60 conditions therein, while a similar pyrometer 34 and a pressure gauge 35 extending into the still indicate when the proper conditions are reached. When the still is operated an oil vapor pressure of from 25 to 300 pounds per square inch is carried 65 therein.

A cracked vapor pipe or line 36 extends from the vapor or upper portion of the still into an elevated carbon and oil separator 33, having a drain pipe 33' provided with a one-way valve *a*, and leading to the bottom of the still for returning thereto the oil which is carried into the separator by the cracked vapors. The separator 33 may be provided with a suitably closed cleaning opening *b* through which the carbon may be 70 removed from time to time as found necessary. In order that this cleaning may take place without necessitating shutting down the apparatus, the vapor line 36 leading to the separator, and the vapor line 36' 75 leading therefrom, are each provided with a valve *c*, which may be closed to cause the vapor to travel through the by-pass *d* and valve *e* therein. It will be apparent that in normal operation the valves *c* are open and the valve *e* closed. The line 36' leads from the separator through an expansion valve 37 to jackets 38, surrounding serpentine portions of the line for feeding in the oil, so that some of the heat of the outgoing cracked 80 vapor is transferred in the interchanger to the ingoing oil. From these jackets, the vapor passes through the pipe 39 of an ordinary condenser 40, the cracked oil and non-condensable gas, in turn, passing from the 85 condenser through the pipe 41 into a receiving tank and scrubber 42, which may be of any desirable type and from which the non-condensable gas is led into any suitable gas 90 receiver.

In order to take care of the free carbon which is constantly formed within the still during the cracking operations, I provide mechanically operated scrapers which continuously scrape the inner wall of the still and remove the carbon therefrom before it becomes packed and hardened. To carry out this operation, I preferably provide a vertical shaft 44, extending centrally into the still through a stuffing box 45 and into a 100 bearing 46. Adjustably secured to the shaft 44 are a plurality of arms 47, each having pivotally mounted thereon a scraper lever 48, having a scraping blade 49, inclined forwardly in the direction of rotation of the shaft. Each of the scraping levers 48 preferably extends rearwardly with relation to the direction of rotation from the pivotal bearings 50, so that the scrapers 49 are pulled around the inner curved surface of the still 2 upon rotation being imparted to the shaft through the worm gear mechanism 51. For maintaining the scraper blades in yielding engagement with the inner surface 105 of the still during the rotation of the shaft, I have provided adjustable weights 52, carried on the bell crank levers 54, pivotally supported on the arms 47. Each of the bell crank levers has a portion 55, engaging the scraper levers rearwardly of their pivotal 110 115 120 125 130

mountings 50, thereby holding the scrapers against the wall, while permitting the same to ride over any irregularities encountered during the travel thereof. The scrapers are preferably so disposed that the paths of travel thereof overlap to insure the cleaning of the entire inner wall of the still. Adjacent the bottom portion of the shaft, I may provide a supplemental scraper 56, adapted to clean the conical portion 6, and insure the feed of carbon therefrom into the carbon receiver.

I claim:

1. In an apparatus for cracking oils, a vertical still, a furnace partly enclosing the same and spaced therefrom, a baffle wall intermediate the furnace and still and forming a heating chamber surrounding the still between the wall and the furnace, and heating means for the furnace, said wall having a plurality of restricted openings forming the only means of communication between the furnace and the still for distributing the heat from said chamber to the still, substantially as described.

2. In an apparatus for cracking oils, a vertical still, a furnace partially enclosing the same and spaced therefrom, a baffle wall intermediate the furnace and still, forming a heating chamber between said wall and the furnace, said wall having its upper end flared outwardly toward the furnace and having a plurality of restricted openings in said flared portion for directing the heated products of combustion from the heating chamber to the upper end of the still, and burners for the heating chamber, substantially as described.

3. In an apparatus for cracking oils, a vertical still, a furnace surrounding the same and spaced therefrom, a baffle wall surrounding the still intermediate the furnace and still forming a heating chamber between the wall and the furnace, said wall having its upper end flared outwardly and joining the furnace adjacent the top thereof and having a plurality of restricted openings therein providing means of escape from the heating chamber adjacent the vapor zone of the still only, and burners extending into said heating chamber, substantially as described.

4. In an apparatus for cracking oils, a vertical still, a furnace surrounding the same and spaced therefrom, a baffle wall intermediate the furnace and still forming a heating chamber between the wall and the furnace, said wall having its upper end flared

outwardly and joining the furnace adjacent the top thereof and having a plurality of restricted openings therein providing means of escape from the heating chamber adjacent the vapor zone of the still, and burners extending tangentially into the heating chamber for breaking up and mixing the products of combustion before they reach said restricted openings, substantially as described.

5. In an apparatus for cracking oils, a still, a heating chamber, there being a plurality of openings permitting the passage of products of combustion from the heating chamber to the still in broken up and distributed condition only, and a stack, there being openings communicating with the stack permitting the discharge of the products of combustion used for heating the still, the total area of said first mentioned openings being substantially equal to the total area of said last mentioned openings, substantially as described.

6. In an apparatus for cracking oils, a still, a heating chamber, there being a plurality of openings permitting the passage of products of combustion from the heating chamber to the still in broken up and distributed condition only, and a stack, there being openings communicating with the stack permitting the discharge of the products of combustion used for heating the still, the total area of said first mentioned openings, the total area of said last mentioned openings and the area of said stack all being substantially equal, substantially as described.

7. In an apparatus for cracking oils, a still, a polygonal furnace partially enclosing the same and spaced therefrom, an annular baffle wall intermediate the furnace and still forming a heating chamber between said wall and the furnace and restricting the flow from the heating chamber to the still, and heating means for the furnace extending into said chamber substantially tangentially to said baffle wall whereby a swirling motion of the products of combustion is produced for breaking up and distributing the same, the angular furnace construction cooperating with said swirling motion for thoroughly breaking up and intermingling said products of combustion, substantially as described.

In testimony whereof, I have hereunto set my hand.

L. B. CUDDY.
